UNITED STATES PATENT OFFICE.

JAMES LEATHEM, OF LEBANON, PENNSYLVANIA.

SEWING MACHINE.

Original application filed September 15, 1920, Serial No. 410,472. Divided and this application filed January 10, 1922. Serial No. 528,258.

To all whom it may concern:

Be it known that I, JAMES LEATHEM, a citizen of the United States, and a resident of Lebanon, in the county of Lebanon and State of Pennsylvania, have invented certain new and useful Improvements in Sewing Machines, of which the following is a specification.

This invention relates to sewing machines, employing a needle having reciprocating as well as oscillating movements such as are used in the stitching of hem stitched seams and the objects of the invention are to simplify and improve the construction of such machines and increase their efficiency of operation so that the same can be run at very high speeds.

The accompanying drawings illustrate one embodiment of my invention, in the several figures of which like parts are similarly designated.

In the drawings:—

Figure 1 is a front elevation of a sewing machine made in accordance with the present invention, shown partly in section and parts broken away for clearness of illustration.

Figure 2 is a bottom view of the sewing machine shown in Figure 1.

30 Figure 3 is an end view, partly in section and with parts broken away of the sewing machine shown in Figure 1.

Figure 4 is a sectional view, with parts broken away on the line 4-4 of Figure 3.

Figure 5 is a sectional view, with parts broken away on the line 5-5 of Figure 1.

Figure 6 is a sectional view, with parts broken away on the line 6—6 of Figure 1.
40 Figure 7 is an enlarged sectional view, with parts broken away of the rear side of the head of the machine.

Referring to the drawings, 1 designates a bed plate; 2 an overhanging hollow arm in which is mounted a needle bar actuating shaft 3 by means of bearing blocks 4. The forward end of the actuating shaft 3 has rigidly secured thereto one end of a crank arm 5 to the other end of which is rotatably mounted one end of a short link 6 the other end of which is rotatably mounted upon an adjustable stud bearing 7 secured to a needle bar 8 suitably mounted in the overhanging arm, the needle bar being re-

ciprocated by the oscillations of the actuating shaft to which it is connected as follows:—

The rearward end of the actuating shaft 3 has adjustably secured thereto one end of a crank arm 9 to the other end of which is rotatably mounted one end of a connecting rod 10 the other end of which is rotatably mounted on a crank 11 forming part of a main driving shaft 12 mounted in suitable bearing blocks 13, 14 and 15 secured to the bottom of the bed plate. 65

The rotation of the main driving shaft 12 through the medium of a suitable pulley 16 acts to reciprocate the connecting rod 10 which oscillates the actuating shaft 3 and it in turn acts through the crank arm 5 link 6 and stud bearing 7 to reciprocate the needle bar 8.

The lower end of the needle bar 8 is provided with a slotted bearing block 17 in which is pivotally mounted by means of a tapered pin 18 the lower end of a needle actuating lever 19 having at its lower end and preferably integral therewith, a needle holder 20 for holding a needle 21. The needle bearing block 17 is also provided with means for holding a piercer 22. The

with means for holding a piercer 22. The upper end of the needle actuating lever 19 is pivoted to a cross head 23 which is arranged to slide in a suitable groove or raceway 24 in a needle oscillating lever 25, in the present instance made L shape. The upper end of the needle oscillating lever 25 is arranged

to fit in a groove 26 in the forward end of the arm in which it is pivoted by means of a pin 27; the lower end of the lever 25 is also arranged to fit in a groove 28 in the forward end of the arm, (the same being pivotally connected, by means of a pivot pin 29, to the forward end of a link 30. The

rearward end of the link 30 is pivotally connected, by means of a pivot pin 31, to the upper end of a slotted segment lever 32, the lower end of which is pivoted to the upright portion of the arm by means of a pivot pin 33. A segmental slot 34 in the lever 32 is arranged to adjustably engage one end of a link 35 by means of a pivot bolt 36, the other end of the link being pivotally connected by means of a pivot pin 37 to one end of a short crank arm 38, the lower end of which is rigidly connect-

ed to one end of a shaft 39 rotatably mounted in the upright portion of the arm, the backwardly extending portion of which is suitably recessed together with the bed plate 5 to permit of free movement of a crank arm 40 the upper end of which is rigidly secured to the shaft 39 adjacent its rear end. The lower end of the crank arm 40 is provided with a roller 41 arranged to engage a 10 cam groove 42 in a circular cam 43 secured to an auxiliary shaft 44 mounted in the bearing blocks 13 and 14. Mounted on the auxiliary shaft 44 is a gear 45 which is arranged to be engaged by a pinion 46 mounted 15 on the main driving shaft 12.

The rotation of the main driving shaft 12 acts through the pinion 46, gear 45, cam 43 and connecting parts to oscillate the needle oscillating lever 25 whose oscillations act to oscillate the needle actuating lever 19 and thereby the needle 21 as the needle bar is reciprocated.

The oscillations of the needle can be regulated by setting the pivot bolt 36 at different positions in the segmental slot 34, any ordinary throw of the needle can be obtained in this manner, further regulations of the throw of the needle can of course be obtained by varying the cam groove in the 30 cam 43.

In the present instance the looping mechanism comprises a rotary hook or loop taker 47 having a vertical shaft 48 rotatably mounted in a bearing block 49. The shaft 35 48 is provided intermediate of its length with a bevel pinion 50 which meshes with a bevel gear 51 mounted on the main driving shaft 12 adjacent the end thereof. The relative sizes of the bevel pinion 50 and the 40 bevel gear 51 to form a hemstitch being such as to impart two rotations to the loop taker 47 to each complete stroke of the needle bar.

In accordance with the present invention 45 the cam groove 42 in the cam 43 is cut to oscillate the needle 21 at proper intervals to form a hemstitch. In the present instance the cam groove 42 is cut to give a substantially straight up and down movement to the needle when a stitch is made on the hem 50 fold of the material, and to oscillate the needle when stitches are made off the hem fold, the cam groove being suitably cut to oscillate the needle to place two stitches off the hem fold to one on.

In that the needle 21 is moved substantially straight up and down when placing a stitch on the hem fold the needle thread does not bind and break during this portion 60 of the stitch even at very high speeds, it being customary to provide a small longitudinal recess on each side of the needle, into which the needle thread fits, to obviate the binding of the needle thread between 65 the needle and the material.

After the needle 21 has been actuated by the cam groove 42 on the cam 43 to place a stitch on the hem fold, the cam groove 42 on the next downward movement of the needle acts to oscillate the needle to place a 70 stitch off the hem fold. After the needle has passed through the material to place the stitch off the hem fold the cam groove 42, on the further downward movement of the needle acts to oscillate the needle toward the rotary hook or loop taker 47 to permit the needle thread to be engaged thereby, in which position the needle is moved by the action of the cam groove 42 substantially straight up and down at the end of its downward movement and at the beginning of its upward movement. On the further upward movement of the needle the cam groove 42 acts to again oscillate the needle 75 away from the loop taker to permit the needle to come out of the material at substantially the same point where the needle entered the material off the hem fold, so as to obviate any tendency to bind the needle thread between the needle and the material 80 to cause the thread to break.

After the needle 21 has been oscillated by the action of the cam groove 42 to place one stitch off the hem fold the cam groove 42 again acts in exactly the same manner to 95 place another stitch off the hem fold, which operation is followed by another series of operations to place another stitch on the hem fold and two off, as before described.

The oscillations of the needle back and forth by the action of the cam groove 42 every time a stitch is placed off the hem fold so that the needle enters and leaves the material at substantially the same point obviates any tendency to bind the needle 100 thread between the needle and the material 105 to cause the thread to break even at the highest speeds.

When the machine is run at very high speeds it is extremely important that there 110 be no binding of the needle thread as it passes through the material, as the slightest binding of any kind will cause it to break, while it is true that the needle is ordinarily provided with a longitudinal recess on both sides, these recesses act to prevent binding only when the needle is reciprocated straight up and down in the material; when however the needle is oscillated to place a stitch off the hem fold the movement of the needle inward to draw the needle thread into engagement with the hook or loop taker, crowds the material up against the needle in such a manner as to bind the needle thread when the needle is withdrawn from the material if this crowding of the material is not relieved.

In accordance with the present invention the crowding of the material against the needle as the needle is withdrawn after plac- 130

ing a stitch off the hem fold is accomplished, as above described, by cutting the cam groove 42 in the cam 43 so that the needle leaves the material at substantially the same point as the needle entered the material, or at such a point as near where the needle originally entered as to be beyond where the material will bind or break the needle thread. The crowding of the material 10 against the needle is not a serious matter when the machine is run at comparatively low speeds but when the machine is run at very high speeds it is absolutely essential that this crowding of the material which 15 acts to bind the needle thread be obviated.

In the present instance the feeding mechanism comprises a feed bar 52 having suitable feed points 53 situated on the top surface of a recessed feed dog 54 secured to 20 said feed bar. One end of said feed bar is pivoted, by means of a bearing pin 55, to the upper ends of two short arms 56, the other ends of which are secured to a rock shaft 57, rotatably mounted on bearing pins 25 58 secured to bearing blocks 59 and 60 secured to the bottom of the bed plate. The rock shaft 57 has adjustably secured thereto a slotted arm 61 in which is adjustably secured one end of a link 62 by means of a 30 pivot bolt 63 the other end of the link 62 being pivoted to one arm of an L shaped lever 64 the centre of which is secured to one end of a sleeve 65 rotatably mounted on a shaft 66 secured to the bearing blocks 35 13 and 14. The other arm of the L shaped lever 64 is provided with a roller 67 which engages a cam groove 68 situated on the side of the gear 45 mounted on the auxiliary shaft 44.

40 The rotation of the main driving shaft 12 acts through the pinion 46 gear 45, cam groove 68, roller 67 and connecting parts to move the feed bar 52 and with it the feed dog 54 back and forth at stated intervals to feed the material backward or forward as may be required. In the present instance the cam groove 68 is arranged to move the feed dog 54 back and forth for every complete stroke of the needle bar. The back and forth movement of the feed dog is regulated by adjusting the pivot bolt 63 in the slotted arm 61 to give any desired feed movement to the feed dog.

45 The other end of the feed bar 52 is slotted 55 to receive a cross head 69 which is pivotally secured to one end of a short arm 70 the other end of which is secured to a rock shaft 71 rotatably mounted on bearing pins 72 secured to bearing blocks 73 and 13 secured to the bottom of the bed plate. The rock shaft 71 has secured thereto one end 60 of a short arm 74 the other end of which is provided with a roller 75 which engages a cam groove 76 in a segmental cam 77 secured to a rock shaft 78 rotatably mounted

on bearing pins 79 secured to bearing blocks 73 and 13. The segmental cam 77 is provided with a slot 80 which engages a cross head 81 pivoted on a disk 82 secured to the end of the auxiliary shaft 44.

70

The rotation of the main driving shaft 12 acts to rotate the auxiliary shaft 44 and it acts through the cross head 81, segmental cam 77 and connecting parts to depress the feed bar 52 and with it the feed dog 54 at 75 stated intervals to feed the material backward or forward as may be required. In the present instance the cam groove 76 is arranged to depress the feed dog 54 to feed the material forward two steps to one step 80 rearwardly.

In accordance with the present invention the upward and downward movement of the feed dog 54 into and out of engagement with the material is regulated to give a 85 relatively slow upward movement of the feed dog, as it engages the material, with a corresponding rapid downward movement of the feed dog as it disengages the material.

The relatively slow upward movement of the feed dog acts to force the material against the bottom of a suitable double presser foot 83 with little or no jar and accordingly without injury to the material, it being important at high speeds to avoid the jar incident to a too rapid engagement of the feed dog with the material which would act to force the material against the bottom of the presser foot in many instances with sufficient force to cut the same.

90

The corresponding rapid downward movement of the feed dog acts to disengage the material instantly without jar or shock allowing the time thus saved to be used on the relatively slow upward movement of 105 the feed bar.

By referring to the drawings it will be seen that when the cam groove 76 acts to depress the feed dog 54 the cross head 81 on the disk 82 is moving in that portion of the slot 80 of the segmental cam 77 which is adjacent the rock shaft 78, which acts to give a rapid downward movement to the feed dog; when however the cam groove 76 acts to raise the feed dog, the cross head 81 on the disk 82 is moving in that portion of the slot 80 of the segmental cam 77 which is away from the rock shaft 78 which acts to give a relatively slow upward movement to the feed dog.

110

In the present instance the double presser foot 83 comprises two presser shoes 84 each of which is suitably pivoted midway of their length to the lower curved ends of shoe arms 85 the upper ends of which are secured to the lower ends of independent presser foot bars 86 each of which is slidably mounted in the end of the overhanging arm 2. The upper end of each of the presser foot bars are preferably made hollow and 125 130

- arranged to enclose coiled springs 87 arranged to be engaged by pins 88 pressed downward by means of suitable caps 89 which screw into the arm 2 to force the 5 shoes 84 into engagement with the material on the feed dog. When in the operation of the machine the feed dog is lowered the overhanging sides of the presser shoes rest upon the feed plate 90.
- 10 The presser shoes 84 are arranged to act on the material entirely independent of each other but the same are arranged to be lifted when not in use by means of a latch 91 pivoted to the arm 2 which engages a projection 15 92 secured to a double collar 93 mounted on both presser foot bars and arranged to be secured to one and slidably mounted on the other. A similar double collar 94 is also provided which is mounted on both 20 presser bars and spaced away from the double collar 93 the same being secured to the opposite presser foot bar and slidably mounted on the other so that the latch 91 will operate both presser shoes at the same 25 time leaving the presser shoes when in operative position to act independently, the double collars 93 and 94 acting to brace the presser foot bars one against the other.
- It is to be noted that the presser foot bars 30 86 are slidably mounted in the end of the arm as nearly adjacent the needle bar 8 as possible, in order to give as nearly as possible a direct upward thrust to the presser bars when the presser shoes are engaged on 35 the upward movement of the feed dog. The mounting of the presser foot bars so nearly adjacent the needle bar is made possible by the fact that the needle bar is reciprocated by the rocking of the actuating shaft 3, 40 less space being required for a reciprocating connection than otherwise would be the case if the actuating shaft 3 was rotated. This arrangement of the presser bars prevents excessive vibration of the presser foot 45 and enables the machine to be run at very high speeds with a uniform feeding of the material.
- The take up mechanism comprises a take up arm 95 arranged to extend upward 50 through a slot 96 in the bed plate, the lower end of said take up arm is integrally secured to a short shaft 97 rotatably mounted in the bearing block 14. The shaft 97 has secured thereto one end of a short arm 98, 55 the other end of which is pivoted by means of a ball joint 99 to one end of a link 100 the other end of which is pivoted by means of a ball joint 101 to the end of an adjustable arm 102 secured to a short shaft 103, rotatably mounted in the bearing block 14. The 60 end of the shaft 103 which projects beyond the end of the bearing block 14 is secured to one end of a guide rod 104 upon which is slidably mounted a slide sleeve 105 having 65 an extended portion 106 which is pivoted by

means of a pivot pin 107 to an extended portion 108 on the lower end of the connecting rod 10.

The rotation of the main driving shaft 12 in a clockwise direction acts through the 70 medium of the slide sleeve 105 to oscillate the guide rod 104 which acts through connecting parts to oscillate the take up arm 95. The position of the slide sleeve 105 on the end of the connecting rod 10 adjacent 75 the crank 11 with the corresponding position of the connecting parts acts to give a rapid movement to the take up arm when the same is moving from left to right to take up additional thread and a relatively 80 slow movement when the take up arm is moving from right to left to let out the thread, together with a gradual acceleration of the take up arm near both ends of its movements.

In other words, the motion of the take up arm is slow while the hook or loop taker 47 is taking the loop of the needle thread which takes place when the take up arm is moving from right to left, while for drawing the stitch tight, which takes place when the take up arm is moving from left to right, the movement of the take up arm is extremely rapid. It will be observed that the slide sleeve 105 is at the lower portion 95 of the guide rod 104 adjacent the shaft 103 when the take up arm is moving from left to right and also near both ends of its movements, permitting relatively fast movement of the take up arm during this time, when, 100 however, the slide sleeve 105 is at the upper portion of the guide rod 104 the take up arm is moving from right to left, permitting relatively slow movement of the take up arm during this time.

The machine above described is capable of running at the rate of forty-five hundred revolutions a minute upward to five thousand revolutions a minute with practically no vibration.

While the invention has been described with particular reference to the details of construction, the same is not to be considered as limited thereto, as many changes can be made and still fall within the scope 115 of the invention set forth in the following claims.

What I claim is:—

1. A high speed sewing machine including in combination, an oscillating needle operating means providing a relatively short reciprocation of the needle bar, a driving shaft, a crank on said driving shaft, means connecting said crank to the oscillating needle operating means, a take-up lever, means pivotally mounting said lever for movement longitudinally of the driving shaft, and means interposed between said connecting means and take-up lever for actuating the latter, said last named means 120

125

130

- being caused to move through a comparatively short path of travel determined by the crank operating said needle oscillating means.
5. 2. A high speed sewing machine including in combination, a needle bar, an operating mechanism therefor involving an oscillating shaft adapted to impart a relatively short reciprocation to said needle bar, a driving shaft, means connecting said driving shaft to said oscillating shaft, a take-up lever, means pivotally mounting said lever for movement axially of the driving shaft and means for actuating said take-up lever, 10 said means including a member having a pivotal connection located at a point in close proximity to the driving shaft and to one side thereof.
3. A high speed sewing machine including in combination, an oscillating needle operating shaft adapted to provide a relatively short reciprocation of the needle, a driving shaft, a crank on said driving shaft, means connecting said crank to the oscillating 15 needle operating shaft, a take-up lever, and means for oscillating said take-up lever, said means including a pivoted member located in close proximity to said crank, and a member slidably mounted on said pivoted member, said slidable member being moved in a relatively small ovoidal path, which path is substantially tangent to the circular path 20 of travel of the crank.
4. A high speed sewing machine including in combination, a needle bar, means including an oscillating shaft for imparting to said bar a relatively short reciprocation, a driving shaft, a crank connecting said driving shaft to the means oscillating the 25 needle bar actuating shaft, a take-up lever, and means connecting said take-up lever to said last named means for moving the lever at varying speeds during each relatively short reciprocation of the needle bar, said 30 last named means operating to describe a relatively short path of travel in the nature of an ovoid adjacent the crank circle described by the operation of said crank.
5. A hem stitching machine comprising in combination, an oscillating shaft, a needle bar driven by said oscillating shaft and having a relatively short reciprocation, a loop taker located to one side of the line of feed 35 of the material, a take-up lever, means pivotally mounting said lever for movement in a plane at right angles to the line of feed, and means for oscillating the take-up lever through a relatively short path of travel commensurate with the relatively short reciprocation of the needle bar, said means being adapted to operate the take-up lever at a relatively slow speed when the loop taker is catching the loop.
6. In a high speed hem stitching machine including an oscillating needle operating 40 means, a driving shaft located beneath the bed plate and having a crank, a pitman rod connecting said crank with the oscillating needle operating means, a take-up lever pivoted below the bed plate and having an arm, a rock shaft having an arm connected with the arm of the take-up lever, the rock shaft carrying a guide rod, and a sleeve 45 slidable on said guide rod and pivotally connected directly with said pitman rod at a point to one side of the axis thereof.
7. In a high speed hem stitching machine including an oscillating needle operating means, a driving shaft located beneath the bed plate and having a crank, a pitman rod connecting said crank with the needle operating means, a take-up lever pivoted below the bed plate and having an arm, a rock shaft located below the plane of said driving 50 shaft and carrying an arm, a link connecting both arms, a guide element carried by the rock shaft, and a slidable member engaged upon said guide element and having an extension pivoted directly upon said pitman rod at one side thereof.
8. A hem stitching machine comprising, in combination, an actuating member including a rock shaft, a pitman rod, a loop taker, a take-up lever connected to said pitman rod and adapted to oscillate in a plane disposed axially of said rock shaft, and means for moving the take-up lever at a 55 slower speed when the loop taker is catching the loop and also when discharging the loop, said means involving a pivoted crank arm, and a link connected to one end of the crank arm, said link having its opposite end connected to the take-up lever.
9. A sewing machine comprising, in combination, an actuating member including a rock shaft and pitman rod, a loop taker, a take-up lever, said lever being connected to said pitman rod and operable in a plane extending axially of said rock shaft, and means for moving the take-up lever at a 60 relatively slow speed when the loop taker is catching the thread and rapidly when the loop is being tightened, and slowing down the movement of the lever when the loop taker is discharging the loop, said means including a pivoted crank arm connected to said pitman rod, and a link connecting said crank arm to the take-up lever.
10. In a high speed sewing machine including an oscillating needle operating means, a driving shaft having a crank, a pitman rod connecting said crank with the oscillating needle operating means, a take-up lever having an arm, a rock shaft arranged at right angles to the pivotal axis of the take-up lever and operatively connected with said arm, a guide rod on the rock shaft extending at right angles thereto, and a sleeve slidable on the guide rod and having an extension pivoted directly on said pitman rod.

man rod, said elements cooperating to oscillate the take-up lever through a short throw and at variable speeds during a cycle of movement.

- 5 11. In a high speed sewing machine including an oscillating needle operating means, a driving shaft having a crank, a pitman rod connecting said crank with the oscillating needle operating means, a take-up lever having an arm, a rock shaft arranged at right angles to the pivotal axis of the take-up lever and operatively connected with said arm, a guide rod on the rock shaft extending at right angles thereto, and a 10 sleeve slidable on the guide rod and having an arm pivoted directly on said pitman rod, said elements cooperating to oscillate the take-up lever through a short throw and at variable speeds during a cycle of movement, 15 20 said sleeve describing an ovoidal path.

12. In a high speed hem stitching machine including needle operating means, a driving shaft located beneath the bed plate and having a crank, a pitman rod connecting said 25 crank with the needle operating means, a take-up lever pivoted beneath the bed plate above the plane of the driving shaft for movement in a plane parallel therewith, an

arm on the pivot of the take-up lever, a rock shaft having an operative connection 30 with said arm and carrying a guide, and a rock shaft operating member slidable along the guide and having an extension pivoted on the pitman.

13. In a sewing machine including an oscillating needle operating means, a driving shaft located beneath the bed plate and having a crank, a pitman connecting said crank with the needle operating means, a take-up lever carried by a rock shaft journaled beneath the bed plate at right angles to the driving shaft, an arm on said rock shaft, a second rock shaft parallel with the driving shaft and carrying an arm pivotally connected with said first named arm, a guide on the second named rock shaft, and a sleeve 40 45 slidable along said guide and having a lateral arm pivotally connected with said pitman rod.

In testimony whereof I have signed this 50 specification in the presence of two subscribing witnesses.

JAMES LEATHEM.
